UNITED STATES PATENT OFFICE.

WILLIAM A. McGINNIS, OF CHICAGO, ILLINOIS,

GARMENT-HANGER.

1,273,253.

Specification of Letters Patent. Patented July 23, 1918.

Application filed May 8, 1916. Serial No. 95,150.

To all whom it may concern:

Be it known that I, WILLIAM A. McGINNIS, a citizen of the United States, and a resident of the city of Chicago, county of Cook, and State of Illinois, have invented certain new and useful Improvements in Garment-Hangers, of which the following is a specification.

My invention relates to improvements in garment hangers and has for its object the provision of an improved construction of this character, which is simple and efficient in use.

The invention consists in the combinations and arrangements of parts hereinafter described and claimed.

The invention will be best understood by reference to the accompanying drawing forming a part of this specification, and in which,

Figure 1 is a vertical section of a garment hanger embodying my invention and shown in position of use,

Fig. 2, a similar view of the same shown partially folded,

Fig. 3, a similar view shown entirely folded,

Fig. 4, a detail view of the hinge connection between spreader arms employed in the construction,

Fig. 5, a detail view illustrating the means for fastening the hanger in folded condition, and

Fig. 6, a detail section illustrating the mounting of a suspending hook employed in the construction.

The preferred form of construction as illustrated in the drawing, comprises two coöperating hanger arms 7 and 8 preferably made of wood and arranged to constitute an ordinary coat rack. At its upper end arm 7 is provided with a central recess 9 and a metallic pivot plate 10 is arranged in said recess and secured therein at one point by means of a screw 11. The plate 10 is further secured in recess 9 by means of a metallic sleeve 12 which is passed through arm 7 and plate 10 as indicated. A suspending hook 13 has its lower end 13' turned laterally as indicated and passed through sleeve 12, the end thereof being up-set as shown.

By this arrangement a pivotal mounting is provided for hook 13 at the same time serving as a means for rigidly anchoring the plate 10 in position. The end 14 of

plate 10 protrudes from the recess 9 as indicated and the upper end of arm 8 is provided with a recess 15 to receive said protruding end, the same being pivotally secured therein by means of a screw 16. The upper end of arm 8 is shaped and arranged to shut against the lower face of arm 7 as indicated to constitute a stop preventing further spreading movement of said arms after they have assumed correct position.

Spreader arms 17 and 18 in the form of channel irons are pivotally connected at their outer ends to the lower ends of arms 7 and 8 and are also pivotally connected centrally by means of a pivot 19, the arm 17 being provided with an extension 20 overlapping the arm 18 to constitute a stop to prevent downward "breaking" of said spreader arms. Arms 17 and 18 are provided with spring clips 21 and 22 so that a pair of trousers may be readily clamped thereon. Recesses 23 and 24 are provided in the lower sides of arms 7 and 8 to receive the spreader arms 17 and 18, and additional recesses 25 and 26 are provided for the accommodation of spring clips 21 and 22. A catch fastening 27 is provided for arms 7 and 8 to hold the same in folded position as indicated in Fig. 5.

By this arrangement, a simple and efficient garment hanger is provided which is capable of economical manufacture and which may be readily folded and extended as desired.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A garment hanger comprising two divergently arranged supporting arms having the inner ends thereof bifurcated to provide kerfs intermediate the side walls of said arms, a metallic plate set in the kerf of one arm, a sleeve extending through said arm and said plate, a hook having its inner end extending through said sleeve and rotatably held therein, means transversely of said arm

holding said plate against movement relative to said arm, said plate having an end thereof protruding from said arm into the kerf of the other arm, and means trans-
5 versely of the last mentioned arm maintain-
ing a pivotal connection between said arm and said plate.

In testimony whereof I have signed my name to this specification in the presence of two subscribing witnesses.

WILLIAM A. McGINNIS.
